UNITED STATES PATENT OFFICE.

ALFRED HARRIS INSINGER, OF PHILADELPHIA, PENNSYLVANIA; CATHARINE L. M. INSINGER, EXECUTRIX OF SAID ALFRED HARRIS INSINGER, DECEASED, ASSIGNEE TO THE INSINGER COMPANY, OF PHILADELPHIA, PENNSYLVANIA, A CORPORATION OF PENNSYLVANIA.

DISH-HOLDING BASKET.

1,298,725.

Specification of Letters Patent. Patented Apr. 1, 1919.

Application filed February 8, 1917. Serial No. 147,292.

To all whom it may concern:

Be it known that I, ALFRED HARRIS INSINGER, a citizen of the United States, and a resident of the city of Philadelphia, county of Philadelphia, State of Pennsylvania, have invented certain new and useful Improvements in Dish-Holding Baskets, of which the following is a specification.

My invention relates to dish holding baskets which are adapted for use upon ship board and also for use for holding dishes which are being washed and cleansed in and by dish washing machines.

It has for one of its objects to provide a basket which may be constructed more cheaply and which is much lighter in weight than such baskets as heretofore constructed have been.

A further object of my invention is to provide a construction of a character in which relatively narrow thin strips of sheet metal may be employed in its manufacture, the said strips being so related and connected together that a substantially rigid construction is produced and so that the dishes whether they be plates, bowls or cups are securely supported and are prevented from becoming broken either in a washing machine or if upon ship board by reason of the tossing and swinging movements of the boat or vessel.

Other objects and advantages of my invention will be pointed out in the detailed description thereof which follows or will be apparent from such description.

In the accompanying drawings I have illustrated two constructional forms of embodiment of my invention, one of which being adapted for receiving and holding bowls while the other is adapted for receiving and holding cups; but it will be understood that changes in the size and shape of the openings for receiving and holding the dishes and in the details of construction may be made without departing from my invention.

In the drawings:

Figure 1 is a top plan view of a basket constructed in accordance with my invention;

Fig. 2 is a longitudinal sectional view of the same taken on the line 2-2 of Fig. 1;

Fig. 3 is an end elevational view looking toward the right in Figs. 1 and 2;

Fig. 4 is an end elevational view looking toward the left in Figs. 1 and 2; and

Fig. 5 is a top plan view of a construction similar to that shown in the preceding figures, but adapted for receiving and holding cups.

In the drawings A and B designate two sections of the basket construction, said sections being hinged together as will be hereinafter pointed out and described in detail. Each of the sections, A and B, is provided with a plurality of lengthwise extending strips or bars, designated respectively as 1 and 2. In the construction shown in Figs. 1 to 4 inclusive of the drawings each of the said sections comprises two lengthwise extending strips while in the construction shown in Fig. 5 each section is provided with three such strips.

The strips 1 of the bottom section A are connected and bound together by the strips 3 and the rectangular shaped frame-like member 4. The strips 3 are secured to up-turned end portions 5 and 6 of the said strips or bars 1 at points a short distance above the lower ends of said up-turned portions and the member 4 is secured to the upper end parts of the up-turned portions 5 and 6. The strips 3 and the member 4 are situated upon the inside of the said up-turned portions, 5 and 6. The opposite ends of the strips 2 are bent and extended upwardly to provide up-turned portions 8 and 10 and to the inside of the upper ends of said portions a rectangular frame 11 is secured by means of rivets or otherwise. The up-turned portions 8 of said strips 2 are connected adjacent to their lower ends by means of a strip 12 situated upon the outer side of said portions.

15 designates rods arranged at intervals and extending between the opposite sides of the respective frame members 4 and 11. 16 designates rods extending lengthwise of the basket between the opposite ends of the said respective frame members 4 and 11, there being one of the said rods for each section in the construction shown in Figs. 1 to 4 inclusive and two of the said rods for each section shown in the construction illustrated

- in Fig. 5. These rods 16 are permanently secured at their opposite ends to the ends of the said frame members and are then twisted or looped around each of the crosswise extending rods 15.
- 20 designates short strips secured to the upwardly extending portions 6 of the section A and extending above the upper ends of said portions. The upper end portions 10 21 of the strips 20 are twisted into planes extending substantially at right angles to the planes of the remaining portions of said strips and are provided with openings for the reception of a pivot rod 22, which rod 15 also extends through openings in the lower portions 23 of the lower ends of strips 24, the upper ends of which extend a distance above the top of the rectangular frame 11 of the section B, as shown in the drawings.
- 20 These strips 24 are connected to the upwardly extending portions 10 of the strips 2. The upper ends of these strips 24 are connected by a cross-bar or strip 25 to form a handle at one end of the basket.
- 25 At the opposite end of the basket upright strips 30 are provided which extend upwardly to a point above the top of the basket. These strips are secured at their lower end portions to the upwardly extending 30 projections 5 of the strips 1. Intermediate their ends these strips 30 are connected by means of a cross strip or bar 31 situated upon their inner sides. Their upper ends are connected by a cross strip or 35 bar 32 situated upon their outer sides. The upper edge of the strip or bar 31 is preferably situated in a horizontal plane a short distance above a horizontal plane extending through the pivot 22.
- 40 When the section B is in closed position, that is, in the position shown in the drawing, the lower edge of the strip 12 secured adjacent to the lower ends and upon the outer sides of the upwardly extending 45 projections 8 of the member 2 rests upon the upper edge of the strip or bar 31. I locate the strip or bar 31 in such position that its upper edge is situated in a horizontal plane above a horizontal plane extending through 50 the axis of the pivot 22 in order that when the swinging end of the section B is lifted or swung upwardly the strip or bar 12 will not contact with or bind against the upright strips 30. Relative positions of the axis of 55 the pivot 22 and the lower edge of the bar 12 being as described it is apparent that from the very beginning of the upward swinging movements of the latter it recedes from the upright strips or bars 30.
- 60 Each of the strips or bars 1 is provided with a plurality of portions 35 which are slightly inclined, being in the construction shown inclined from the pivoted end of the basket toward the opposite end. Each of 65 these portions 35 terminates in a shoulder 36; that is to say, each portion 35 is separated from the next adjacent portion 35 by an abutment or shoulder 36. By reason of the fact that the portions 35 are slightly inclined the tendency is to cause the edges of the dishes to slide forward. The abutments or shoulders, however, constitute the limit of such sliding or forward movement and such shoulders are so positioned relatively to the cross-rods 15 that when the edges of the dishes are seated against the shoulders, as indicated by dotted lines in the drawings, the said dishes are sustained in a substantially vertical position between the transverse rods 15 and the longitudinally extending rods 16.
- It is desirable that the dishes be held in such substantially vertical position because if they were permitted to occupy an inclined position so that the open ends of the bowls, 81 cups, etc., should point or face upwardly or in an upward direction a small amount of water would be retained in the lower sides of the bowls or cups which would be highly objectionable.
- The construction shown in Fig. 5 is identical in principle with that shown in the preceding figures of the drawings, the only difference being that the twelve receptacles or compartments for the cups are divided into 95 three groups of four each instead of into two groups of six each as in the construction shown in the said preceding figures.
- It will be apparent that I have provided a construction which is very hygienic and 10 sanitary for the reason that there are a minimum number of crevices in which foreign matter may lodge.
- Furthermore my construction not only is extremely light but it is very durable and 101 is adapted to and does support the dishes, whether they be in a washing machine or on board a boat or vessel, in a manner to prevent or at least reduce breakage to a minimum.
- I claim:—
- A dish holding basket comprising a plurality of relatively narrow thin strips of sheet material extending in directions parallel with two opposing sides of said basket, 115 said strips each being provided with downwardly gradually inclined portions terminating in upwardly extending shoulders, said portions being arranged in succession longitudinally of the said strips, said strips 120 being provided at their opposite ends with upwardly projecting portions, a frame member of rectangular shape secured to the said upwardly projecting portions and being spaced a distance from said strips, said 125 frame consisting of a relatively thin narrow strip of sheet metal, parallel rods extending in directions substantially at right angles to the first named strips and secured at their ends to opposing sides of the frame member, 130

said rods being situated in substantially vertical alinement with said shoulders, one or more rods extending substantially at right angles to the last mentioned rods and having rigid connection therewith and being connected at their opposite ends to opposing ends of said frame member, the said second

named rods being situated in vertical planes intermediate said first mentioned strips, substantially as described.

In testimony that I claim the foregoing as my invention, I have hereunto signed my name this 3rd day of February A. D. 1917.

ALFRED HARRIS INSINGER.
